(57) CLAIM

The ornamental design for a shoe as shown and described.

DESCRIPTION

FIG. 1 is a perspective view of a shoe, showing our new design.

FIG. 2 is a side view of the shoe of FIG. 1, showing our new design.

FIG. 3 is another side view of the shoe of FIG. 1, showing our new design.

FIG. 4 is a front view of the shoe of FIG. 1, showing our new design.

FIG. 5 is a back view of the shoe of FIG. 1, showing our new design.

FIG. 6 is a top view of the shoe of FIG. 1, showing our new design; and,

FIG. 7 is a bottom view of the shoe of FIG. 1, showing our new design.

The broken lines indicate portions of the shoe that form no part of the claimed design.

1 Claim, 7 Drawing Sheets
